UNITED STATES PATENT OFFICE.

CLYDE S. CORRIGAN, OF NORWOOD, OHIO.

HOLDING DEVICE FOR DEEP-WELL MACHINES.

1,406,350.

Specification of Letters Patent. Patented Feb. 14, 1922.

Application filed September 4, 1920. Serial No. 408,119.

To all whom it may concern:

Be it known that I, CLYDE S. CORRIGAN, a citizen of the United States, residing at Norwood, in the county of Hamilton and State of Ohio, have invented a new and useful Holding Device for Deep-Well Machines, of which the following is a specification.

My invention is an improvement in holding devices for all deep well machines that are lowered into the well by flexible, sustaining and power conveying cable, and known as motor advancing deep well machines on account of the fact that the motor 10 is attached to the working parts of the machines and advances with it into the well. This holding device is provided with motor operated, link connected holding elements that will make rigid connection with the 15 walls of the well, and prevent rotary or vertical motion with respect thereto when used.

First, as a fulcrum by any deep well machine performing work, such as boring, reaming, bailing, etc.:—second, to hold a 20 machine at a certain vertical position, so that its working parts may be raised to the work at a predetermined rate of pressure;—third, to prevent slackening or tightening of the sustaining cable, from interfering with 25 the operation of a machine;—fourth:—to act as a fulcrum to hold a machine in a certain vertical plane while its cutting elements are raised in that plane for making vertical side slots from the well, also while the cutting elements of a machine so held are raised 30 to a horizontal plane and rotated in that plane as in making underground tanks and cisterns.

The holding device may be operated by 35 the same power that operates the machine it holds, either electric, water or compressed air. The fulcrum member may be either the outside of a rod, or the inside of a casing and may be a part of the holding device or 40 a part of the machine held by it.

With these and other objects in view, a preferred form of construction of the holding device is illustrated in the accompanying drawings, in which like numerals refer to 45 similar parts throughout.

Fig. 1, a view of the holding device with reaming machine attached.

Fig. 2, a view of the holding device with deep well machine attached.

Fig. 3, a sectional view of the device with saw tooth holding elements.

Fig. 4, a sectional view of the device with spike tooth holding elements.

Fig. 5, a sectional plan at 5—5 Fig. 3.

Fig. 6, a sectional plan at 6—6 Fig. 4. 60

The holding device primarily consists of a casing 1, with a plurality of slots in the sides and interchangeable link connected holding elements 2 positioned therein, the length and shape of said holding elements, 65 and the size and kind of teeth used, may be varied to suit the various materials which the well penetrates.

In the upper part of casing 1 is a motor 3, which operates a screw 4 to move the hollow push rod 5, by which spread links 7 are moved to force the holding elements 2 firmly against the sides of the well; adjacent to push rod 5 and operated thereby, is shunt circuit breaker 6. 70

Spread links 7 are pivotally attached to lugs 8 on push rod 5, and attached to holding elements 2 by slot and pin connections, they are provided with cushion springs 9, that are compressed after the teeth of 80 the holding elements 2, have come in contact with the walls of the well, so that in case any of the earthy material is loosened, the springs will force the teeth forward against the solid earthy material beneath. 85

Supporting links 10 are pivotally attached to lugs 11 on casing 1, and to the upper end of holding elements 2 as shown in Fig. 3. If holding means 2 are of the form shown in Figure 4, guide lugs 12 are 90 used to hold them in place when in closed position.

Centrally positioned in casing 1 is a hollow rod 13, held in place by top plate 1^a, and bottom plate 1^b, it acts as a hub to hold rod 95 5 and motor 3 in position, and also as a passage way to lead power wires 14, and control wires 15, from the supporting cable 16 down past the holding mechanism to lugs 19 on the bottom of plate 1^b. 100

Handle 18, fastened to the top of casing 1, may be of any shape suitable for attaching supporting cable 16, power wires 14 lead direct from cable 16 to motor 3 and shunt circuit breaker 6, thence to lug 19 and to the 105 machine held by this device, control wires 15 lead direct from cable 16 to lug 19 and to the machine held by this device, power wires 14 and control wires 15, are attached to lugs 19 so that there will be no strain at the 110 point 17 where they leave supporting cable 16.

When the deep well machine held by this device is operated in a fulcrum casing 20, as shown in Fig. 1, said casing is attached to, or is an extension of, casing 1. When operated on a fulcrum rod 21, as shown in Fig. 2, said rod is attached to or is in an extension of rod 13. Fulcrum member 20 or 21 may be either a part of the holding device or a part of the machine held thereby.

10 The operation of the holding device is as follows: When any motor advancing type of deep well machine held by it has reached the bottom of the well or the point at which it is to perform work, and transmitted the required signal to the operator at the surface, he switches on the power current and operates motor 3 which moves rod 5 and links 7, thereby causing holding elements 2 to dig into the walls of the well and com-

20 press cushion springs 9, after which the head of push rod 5 closes shunt circuit breaker 6, and shunts most of the power current to the machine held, but leaving sufficient power to produce enough torque in

25 motor 3 to hold push rod 5 and holding means 2 in position, thereby preventing casing 1, and the fulcrum member attached thereto, from rotary or vertical movement with respect to the walls of the well, while

30 the machine held thereby is exerting force to perform its work.

When the machine held has performed the required amount of work and operated the required signal at the surface, or at 35 will, the operator may reverse the power current, the motors of the machine held reverse quickly and perform their closing operations before the slow motion of motor 3 on shunt current opens circuit breaker 6,

40 then motor 3 operates quickly and draws holding elements 2 back to casing 1, so that the holding device and the machine held by it may be raised to the surface.

As I am not aware of any holding device, 45 of the character described, capable of holding all kinds of motor advancing deep well machines, that depend on electric or fluid power for operation, I claim this device as new and broadly patentable.

50 Having described the construction and operation of my invention, what I claim as new and desire to secure by Letters Patent is:

1. In a holding device adapted to be lowered into a well with a deep well machine movably attached, the combination of a casing, a plurality of toothed holding elements positioned in slots therein, a central push rod, radial spreader links pivotally connecting said holding elements to said push rod, power means of moving said push rod, and forcing said holding elements out of said casing and against the walls of the well with sufficient force to make rigid connection therewith, and prevent rotary or

longitudinal motion, when used as a fulcrum while the attached machine is exerting force to perform work, and means of reversing said power means, and releasing said holding elements from the walls of the well, for 70 lifting to the surface.

2. In a holding device of the character described, the combination of a casing with a plurality of slots in the sides, a plurality of link connected holding elements radially positioned in said slots, power means of forcing said holding elements out against the walls of the well, an extending fulcrum against which a machine held by it may exert force to perform work. 75

3. In a holding device of the character described, the combination of a casing, a plurality of link connected interchangeable holding elements radially positioned in slots in the sides thereof, power means of extending said holding elements out against the sides of the well, with sufficient force to make rigid contact therewith, an extending fulcrum against which a machine held by it may exert force to perform work, and 80 means of detaching said holding elements from the walls of the well for lifting both machines to the surface. 85

4. In a holding device of the character described, the combination of a casing with a plurality of openings therein, a plurality of toothed holding elements slidably positioned in said openings, a centrally positioned push rod with radial links pivotally connected to lugs on said push rod, and to said holding 100 elements, power means for moving said push rod and the end of links attached thereto, and extending the other end of links so that the attached holding elements will make rigid connection with the walls of the well, 105 and hold the device from rotary or vertical motion with respect thereto, when used as a fulcrum against which deep well machines may exert force to perform work. 110

5. In a holding device of the character described, the combination of a casing, a plurality of holding elements radially positioned in slots therein, power means and radial link members to force said holding elements against the walls of the well said 115 links having slotted holes for pins connecting them to holding elements, springs enclosed in said links to press pins of holding elements against end of slot until the holding elements are pressed firmly against 120 the walls of the well, then extending said links to the final holding position, thereby compressing springs or extending the holding elements farther and more firmly into depressions or soft formations in the walls 125 of the well.

6. In a holding device adapted to be lowered into a well while holding a deep well machine, the combination of a casing, a plurality of motor operated link connected hold- 130

- ing elements positioned in slots therein, a motor for extending said holding elements against the walls of the well with sufficient force to prevent rotary or vertical motion with respect thereto, means of shunting the motive power to the deep well machine, except a small portion necessary to produce sufficient torque in the motor to hold said holding elements in the holding position, 10 said motor being reversible, thereby breaking said shunt circuit and detaching said holding elements from the walls of the well.
7. In a holding device of the character described, the combination of a casing with a 15 plurality of slots, motor operated link connected interchangeable holding elements slidably positioned in said slots, and a plurality of teeth in each holding element, or such shapes as to enable them to penetrate 20 the various materials the well passes through, with sufficient force to prevent the holding device from rotary or longitudinal motion when used as a fulcrum by a machine exerting force to perform work.
8. In a holding device of the character described, the combination of a casing with a plurality of openings in the sides, a plurality of motor operated holding elements radially positioned therein, and a hollow rod centrally positioned in said casing, to afford 30 a convenient passage way for power and control means, from the sustaining means down past the holding elements.
9. In a holding device of the character described, the combination of a fulcrum member, a plurality of holding members, interchangeable link members for extending said holding members to any desired radius, springs enclosed in said link members, power means of operating said link members to extend said holding members against the walls of a well, thereby compressing said springs, or not, as required to cause each holding member to make firm holding engagement with uneven or yielding portions of the 40 walls of a well, for the purposes described. 45
